(57) **CLAIM**

We claim the ornamental design for an seat assembly, as
shown and described.

DESCRIPTION

FIG. 1 is a perspective view of a seat assembly according to an
embodiment of the invention with the seat member disposed
above the base and the seat being folded down.

FIG. 2 is a perspective view of a seat assembly according to an
embodiment of the invention with the seat member coupled to
the base member and the seat being folded up.

FIG. 3 is a first side elevational view of the seat assembly with
the seat and base members coupled and the seat folded down.

FIG. 4 is a rear elevational view of the seat assembly of FIG.
3.

FIG. 5 is a second side elevational view of the seat assembly
of FIG. 3.

FIG. 6 is a front elevational view of the seat assembly of FIG.
3.

FIG. 7 is a top plan form view of the seat assembly of FIG. 3;
and,

FIG. 8 is a bottom plan form view of the seat assembly of FIG.
3.

The short dashed lines shown on the seat cushion in FIGS. 2,
7, and 8 are understood to represent stitching.
